MACHINE FOR CLOSING THE ENDS OF
COLLAPSIBLE TUBES

Joseph Mankiewicz, Maplewood, N. J., assignor,
by mesne assignments, to Lusteroid Container
Company, South Orange, N. J.

Application February 26, 1931, Serial No. 518,376

6 Claims. (Cl. 113—54)

This invention relates to an improved machine for fastening clips to the flat ends of collapsible tubes. The flat ends are provided, in practice, with metal clips which are folded over and then 5 squeezed or compressed to make a tight closure. The machine is operated twice, once to fold the tube and then to compress it. The machine is preferably manually operated and is simply constructed and does not endanger the fingers of 10 the operator:

The invention is illustrated in the accompanying drawing in which Figure 1 is a perspective view of the machine in partly closed position. Figure 2 is a cross section of the machine in open 15 position, said section being taken on a plane indicated by line 2—2 in Figure 1. Figure 3 is a similar section showing the machine folding the end of a tube and Figure 4 is a section showing the machine compressing a tube. Figure 5 is an 20 end view of one form of clip used on a tube and Figure 6 is an enlarged section showing the complete closure.

The machine comprises two elements hinged together at the back and the preferred form is 25 used on a bench or table. The embodiment that is illustrated in the drawing has one element represented by a base 10 and the other element by a cover 11 which cover is recessed or inclined on its under side as at 11a. These are hinged together as at 12, at one edge and spaced apart to 30 form a gap 13 to allow space for the folding over of the flat end of a tube. The cover is operated by a handle 14. The flat tube is provided with a clip 15 or its equivalent. The cover is made to 35 receive this end so provided and is recessed as at 16 for this purpose. The recess 16 in the cover has a lip which forms a relatively thin wall 17 which wall forms the initial bend in the tube when the cover is brought forward and being thin 40 it forms a tight fold. The other wall 18 of the recess bears on the outside of the fold in the tube. The recessed part of the base is indicated at 10a and acts as a guide to facilitate the placing of the tube in the machine for the first or 45 bending operation. The tube is limited in its insertion by an adjustable plate 19 in the cover. The plate 19 is adjusted to various sizes of tubes or clips to vary the width of the fold. The plate 19 can be secured in adjusted position by the 50 screws 20 which pass through the slots 21 in the plate 19.

The end of the tube with the clip 15 on it is inserted into the space or recess in the cover at its 55 hinged end and the tube lies in the recessed part 10a. This will be clear from Figure 2. The han-

dle 14 is then pulled over which pulls the cover over and this operation bends the tube and the clip over to the position shown in Figure 3. The cover is then lifted and the tube is also lifted by the operator to a position nearly back to the 5 position from which the cover started and the tube is easily pushed back to release its bent end from the cover. The tube is then placed with its folded end on the anvil 22 which anvil lies alongside the depressed part 10a of the base 10. The 10 cover is again pulled over by the handle 14 and the cover and the anvil co-operate to flatten or crimp the clip and the end of the tube. This step is shown in Figure 4. The tube can be positioned by a yielding gage such as provided by 15 the two pins 23 which yield to pressure from the cover by reason of the supporting springs 24 placed under the pins. The anvil is inclined upward relative to the hinged end of the machine and the recessed part is inclined downwardly 20 from the said hinged end of the machine. They are also arranged side by side and this arrangement permits the operator to close the end of 25 the tube by two partial closings of the cover.

The underside of the cover is inclined away 25 from the recessed edge to provide a clearance. This divergence of the under surface of the cover is sufficient to protect the filled collapsible tube against compression or damage while the clip and flat end of the tube are curled enough to put 30 the parts in a shape to be fully compressed by the operation on the anvil 22. This will be clearly seen from the clearance shown in Figure 3.

When the last operation is completed the tube is folded at the end as in Figure 6 and the machine is placed in the position shown in Figure 2 ready for the primary operation on another 35 tube.

When folding celluloid tubes it is sometimes desirable to heat the cover 11 to more easily bend 40 the material of the tube and I install an electric heater 25 at a suitable place on the cover.

Various changes may be made in the arrangements and proportion of the parts without departing from the scope of the invention. 45

I claim:

1. A machine for closing the ends of collapsible tubes comprising a base the top surface of which is provided with a depressed part, said base adapted also to provide a raised anvil portion, 50 a cover hinged to the back of the base and having a recessed edge to receive the closed end extending across to engage the anvil whereby a tube in the recess can be partly crimped by one movement of the cover and can be completely 55

crimped by engagement between the cover and the anvil.

2. A machine for closing the ends of collapsible tubes comprising a base with a hinge at the back and having a recessed portion extending downwardly toward the front, said base adapted also to provide an anvil extending upwardly toward the front, the recess and anvil being side by side, a cover hinged at the back to the

10 hinge of the base and extending across both the recess in the base and the anvil, the hinged end of the cover having an inclined part on the under side and a narrow recess in its edge, one wall of the recess being relatively thin, said base adapted further to provide at its outer end a

15 support for a yielding gage.

3. A machine for closing the ends of collapsible tubes comprising a base with a hinge at the back and having a recessed portion extending downwardly toward the front, said base adapted also to provide an anvil extending upwardly toward the front, the recess and anvil being side by side, a cover hinged at the back to the hinge of the base and extending across both the recess in the base and the anvil, the hinged end of the cover having an inclined part on the under side and a narrow recess in its edge, one wall of the recess being relatively thin and an adjustable plate inside the cover with one edge forming the rear face of the recess in the cover whereby the depth of the recess can be varied.

4. A machine for closing the ends of collapsible tubes comprising a base with a hinge at the back and having a recessed portion extending downwardly toward the front, said base adapted also to provide an anvil extending upwardly toward the front, the recess and anvil being side by side, a cover hinged at the back to the hinge of the base and extending across both the recess in the base and the anvil, the hinged end

of the cover having an inclined part on the under side and a narrow recess in its edge, one wall of the recess being relatively thin and an adjustable plate inside the cover with one edge forming the rear face of the recess in the cover whereby the depth of the recess can be varied and a heating element on the cover, one end of said plate projecting from the cover for manipulating the plate for adjustment.

5. A machine for closing the ends of collapsible tubes comprising a base with a hinge at the back and having a recessed portion extending downwardly toward the front, said base adapted also to provide an anvil extending upwardly toward the front, the recess and anvil being side by side, a cover hinged at the back to the hinge of the base and extending across both the recess in the base and the anvil, the hinged end of the cover having an inclined part on the under side and a narrow recess in its edge, one wall of the recess being relatively thin and an adjustable plate inside the cover and with one edge forming the rear face of the recess in the cover whereby the depth of the recess can be varied, one end of said plate projecting from the cover for manipulating the plate for adjustment.

6. A machine for closing the ends of collapsible tubes comprising a base, a cover, the cover being hinged at one end to the base and spaced therefrom to permit the folding of the end of a tube, and having a recess having a narrow edge to fold the tube when the cover is partly closed, said base adapted also to provide an anvil on which the folded tube can be compressed to complete the fold by a complete movement of the cover, said base being further adapted to provide a support for resiliently mounted pins.

JOSEPH MANKIEWICZ.
